WALLACE R. DOUGLAS, WILLIAM H. DOUGLAS, AND DONALD Q. DOUGLAS, OF CRETE,
NEBRASKA

VOTING BOOTH

Application filed December 11, 1928. Serial No. 325,176.

Our invention relates to voting booths and its primary object is the provision of a combined container and collapsible voting booth of integral construction.

5 An important object of our invention is the provision of a collapsible voting booth which is simple in construction and simple in its folding and unfolding operation.

Another of our objects is the provision 10 of a structure of the class specified which is light in weight and which has great strength to withstand the rough usage to which it is put.

Another object which we have in view is 15 the provision of a voting booth attached to a container and foldable therein, the container having space within which to store blanks or records or other material, the whole structure being fireproof.

20 Having in view these objects and others which will be pointed out in the following description, we will now refer to the drawings, in which

Figure 1 is a view in perspective of a 25 single stall voting booth embodying the novel structure.

Figure 2 is an illustration showing the keyhole slot joint which we employ in several connections in our voting booth.

30 Figure 3 is an illustration showing the break joint linkage employed on some of the braces of our voting booth.

Figure 4 is an illustration showing on an 35 enlarged scale the latch between the first and second sections of the rear uprights.

Figure 5 is a view of a modification showing how the voting booth may be constructed in two stall form by means of very slight modification of the Figure 1 construction.

40 The container 10 is preferably made from sheet metal which is heavily reinforced at its edges. When open as shown in Figure 1, the top and the forward end are open.

45 The lid 11 is hinged at 12 and it is provided with flanges at the lateral edges and with the flange closure 13 for the forward open end of the container. The container is further provided with a hasp 14 whereby a

50 padlock may be used to prevent unauthorized

access to the container. There is also provided one or more handles 15 for convenience in transportation.

The booth frame proper is pivotally secured to the container at the lower rear corner edge thereof. This frame includes two uprights each having the three sections 16, 17 and 18 of substantially equal lengths and pivotally connected so as to be foldable over each other. The two sections 16 are interconnected by means of crossed braces 19 which are connected with each other at their crossing point. The sections 16 and 17 are pivotally connected together and the section 17 is provided at its lower extremity with a sliding clip 20, the lower end portion of which is adapted to overlap the section 16 in the manner best shown in Figure 4. The clip 20 may be readily released by moving it upward to disengage from the section 16 whereupon the two sections are foldable on each other. At the junction of the sections 17 and 18 is a shelf 21 which is connected by means of a common pivot to the sections 17 and 18. This shelf is secured to the section 17 by means of the braces 22 and to the section 18 through the braces 23. The braces 22 and 23 are each formed from a pair of pivotally connected straps having a break joint as best shown in Figure 3. The sections 16 are held in their upright position by means of braces 24 having a construction similar to the braces 22 and 23. The top 25 of the booth is rectangular in form and it is pivotally secured to the sections 18 at 55 their upper extremities, having a pivotal movement of substantially three quadrants from the horizontal position to the vertical depending position. The top 25 is held in its operative position by means of braces 26 connecting the sides of the top with the sections 18. These braces have releasable connections with the sides of the top, these connections being preferably rivets protruding from the sides of the top and keyhole slots in the braces for engaging the protruding rivets.

The voting booth as above described is set up in the manner shown in Figure 1. The lid or cover 11 of the container is utilized 100

for partially covering the rear of the booth and it is provided with means for engaging the sections 17 of the uprights in order to hold it in position. The forward portion of 5 the top 25 is provided with a pair of projections at its middle point. The curtain 27, which is preferably made from a single piece of canvas of rectangular form, is secured at two of its corners to the projections at 10 the forward end of the top 25 so that it is folded around both sides and the rear of the booth and so that it covers the front of the booth with its meeting edges arranged so that entrance may be had by pushing aside 15 the front flaps of the canvas 27. The metal clips 28 are also secured to the canvas at its upper edge and these clips are adapted to engage the top 25 to support the canvas.

The booth as above described is a single 20 stall booth which is secured to a container and which is collapsible into the container. It is sometimes desirable, however, that two stalls be provided in a single unit and this may readily be done with slight modification 25 of the Figure 1 construction as shown in Figure 5. In this case the container consists of four parts 29, 30, 31 and 32, all hinged together in a manner such that the opening of the container leaves all of its 30 four parts flat on the floor. The uprights each consist of three parts 33, 34 and 35 which are similar in all respects to the corresponding parts of the booth shown in Figure 1. The braces and latching devices for 35 holding the sections of the uprights in vertical position and the devices for holding the shelf 36 in operative position are all similar to the corresponding parts in the single stall booth. A second shelf 37 is secured to the 40 uprights to project rearwardly therefrom. This shelf is hinged to the uprights and is positioned slightly below the level of the shelf 36. In its operative position the shelf 37 is supported by a pair of 45 braces 38 which have releasable connections at one end. There is also provided a second top 39 which is foldable over the top 40 in the collapsible position of the booth and which projects rearwardly from the 50 uprights. The tops 39 and 40 are preferably connected to each other and to the uprights by pivot pins passing through all three of the members. The top 39 differs from the top 40 also in that it is U-shaped instead of 55 rectangular. A permanent wall 41 is secured to the uprights to separate the two stalls of the booth. This wall may be made from canvas similar to the outer walls but since it need not be flexible, any other desired material such as sheet steel may be used as a 60 partition wall. The outer walls, however, must be of flexible material of which canvas is preferably the most suitable. The wall 42 differs from the wall 27 only in that it is 65 formed of two parts instead of one. Each

part of the wall 42 extends around one half of the two stall booth so that entrance may be gained to either stall by simply separating the canvas at its meeting edges in the middle portion of the front and rear stalls. The top 39 is braced to the uprights by means of 70 braces 43 having releasable connections with the top.

Our voting booth will be found to be admirably adapted for use in numerous places in which the older style voting booths do not give entire satisfaction. In small polling places requiring only one or two stalls, the booth will serve the purpose better than the prior voting booths because it may be readily 75 folded into a compact bundle and stored in a small space when not in use. The booth is particularly useful at the present time since so many of the election boards have women members who find it difficult to manipulate the older style of voting booths, especially those consisting of numerous detached parts which must all be placed in the proper locations. The present voting booth has the advantage of light weight and extreme ease of 80 manipulation. It is only necessary to open the container and to unfold the parts by extending the uprights. Each brace is firmly 85 secured and its normal action is perfectly obvious to even the least mechanically inclined women.

When folded and stored the booth is entirely protected by the walls of the container which entirely enclose it. The canvas is loosely stored within the container which has ample space for the storage of blanks, records and other material. The walls of the container are of steel which furnish fire-proof protection for the contents. Even in the almost impossible event that fire should start within the container the fire will soon be smothered from lack of air so that the contents will be protected. When the booth is erect and in use, it is fireproof since the frame is an all steel frame. The canvas for 100 the walls may be impregnated with a fire-proofing chemical which will make the entire booth fireproof under any and all conditions.

Having thus described our invention in such full, clear, and exact terms that its construction and operation will be readily understood by others skilled in the art to which it pertains, what we claim as new and desire to secure by Letters Patent of the 115 United States is:

1. A voting booth including a base, a pair of rear uprights pivotally secured thereto and foldable thereon, each of said uprights consisting of three sections pivotally secured 120 together in end to end relation and foldable into parallelism, releasable means for maintaining said sections in erect relation, a top frame pivotally secured to the upper pair of said sections and foldable thereon, re- 125 130

leasable braces between said top frame and said uprights for releasably maintaining said top frame in horizontal position, a shelf secured to said uprights at the pivotal connections between two of the pairs of said sections, and a pair of break joint braces at each side of said shelf and secured to said uprights at points above and below said shelf.

10 2. A voting booth and a container therefor, said container having a base adapted to serve as a floor for said voting booth, a pair of rear uprights secured to said base and foldable thereon, each of said uprights consisting of three sections pivotally secured together in end to end relation and foldable into parallelism, releasable means for maintaining said sections in erect relation, a top frame pivotally secured to the upper pair of 15 said sections and foldable thereon, releasable braces between said top frame and said uprights for releasably maintaining said top frame in horizontal position, a shelf secured to said uprights at the pivotal connections 20 between two of the pairs of said sections, and a pair of break joint braces at each side of said shelf and secured to said uprights at points above and below said shelf, said container having a closure whereby said container and closure are adapted to entirely 25 enclose said voting booth when the parts thereof are in their folded relation.

3. A voting booth including a pair of uprights each consisting of a plurality of sections pivotally connected together in end 30 to end relation and having means for releasably holding said sections in erect relation, a pair of top frames pivotally secured to said uprights at the upper extremities 35 thereof, said top frames normally projecting forwardly and rearwardly respectively from said uprights and being foldable thereagainst, releasable braces for holding said top frames in horizontal position, a pair of shelves secured to said uprights and 40 projecting forwardly and rearwardly respectively therefrom, the first of said shelves being secured to said uprights at the pivotal connections between two pairs of said 45 uprights and having break joint braces connecting the first of said shelves to the uprights at points above and below their pivotal connection, and the second of said shelves being pivotally secured to said uprights 50 at points below the first of said shelves, said shelves being foldable against said sections, and a brace for releasably holding the second of said shelves in horizontal position.

60 In testimony whereof we affix our signatures.

WALLACE R. DOUGLAS.
